**FLUID COOLED APPARATUS WITH NATURAL
AND FORCED COOLING**

William C. Sealey, Wauwatosa, Wis., assignor to Allis-Chalmers Manufacturing Company, Milwaukee, Wis.

Application January 7, 1953, Serial No. 329,977

13 Claims. (Cl. 257—191)

This invention relates generally to apparatus provided with fluid by which heat is dissipated and particularly to electrical apparatus, such as transformers, that are embodied in casings having heat dissipators and provided with cooling fluid, such as insulating oil, which is circulated under certain conditions by natural convection and under other conditions by a pump for increasing the rate of flow of the fluid through the heat dissipators.

Various heat exchange means or systems have been provided for cooling electrical apparatus, such as transformers. In those systems heat of the transformer is transferred from the coils and core thereof to the oil or other cooling fluid by conduction, thereby causing that fluid to flow by convection to eventually transfer the heat by conduction to the material of the casing and radiators attached thereto, from which the heat is transferred by radiation and conduction to the cooling air surrounding the casing and radiators. In such apparatus, where the transformer heats the cooling fluid to cause it to flow by convection in a natural circulatory path upwardly through the transformer disposed in the casing and downwardly through the radiator external of the casing, the system will be generally referred to hereinafter as a self-cooled system having a self-cooled rating. And where a fluid pump is provided to increase the rate of circulation of fluid, the system will be referred to as forced fluid, having a forced fluid cooled rating.

While it has been suggested that encased transformers may have both these systems adapted thereto, such transformers have had to be provided with separate heat dissipators for the two systems involving considerable expense, or the flow of fluid by natural convection in the self-cooled system has been considerably restricted because of passing through the pump of the other system, or a bypass and valves or excessively large passages in the pump have had to be provided so as not to impede the natural convection system. It has also been suggested that the pump and parts of its system may be embodied in the transformer casing, but that results in an increase of the size of the casing and complicates the design of the transformer because of the added insulation problems. And naturally, it is impractical to change transformers embodying only a self-cooled system to add an internally arranged pump of a forced flow system.

In accordance with the teachings of this invention those two systems may be combined in an improved way eliminating the necessity for separate heat exchangers in the forced fluid flow system and eliminating the necessity of an internal pump. The above mentioned disadvantages are avoided by constructing and arranging the apparatus, its casing and cooling systems in accordance with this invention in such manner as to provide a fluid pump preferably disposed externally of the casing and arranging that pump and its intake and discharge with respect to the radiators so that the natural convection flow of the fluid in the self-cooled system does not pass through the pump but still utilizes the same radiators as the forced fluid flow system without providing a specially arranged

2

valve or a bypass of the pump. Further, in accordance with the teaching of this invention apparatus now provided with conventional radiators of only a self-cooled system may relatively easily and with minimum expense be provided with an efficient forced fluid system without additional radiators, valves or bypasses and without lessening the effectiveness of the self-cooled system.

It is therefore an object of this invention to provide an improved cooling system for apparatus subject to changes in temperature designed to have both the so-called forced fluid cooled rating and self-cooled rating.

Another object of this invention is to simplify the structure and construction of cooling system apparatus of transformers, or the like, designed to have self-cooled rating and forced fluid cooled rating.

Still another object of this invention is to provide for transformers or the like encased apparatus, self-cooled rating and forced fluid cooled rating by such means for circulating the fluid in the forced fluid system that does not interfere with the self-cooled rating and thereby does not lessen the effectiveness of the self-cooled system and in which the self-cooled system of the encased electrical apparatus is as efficient and inexpensive as a similar self-cooled system designed for a similar electrical apparatus not provided with a forced fluid system.

And another object of this invention is to provide an inexpensive forced fluid apparatus to be easily and inexpensively added to self-cooled transformers.

Objects and advantages other than those above set forth will be apparent from the following description when read in connection with the accompanying drawings, in which:

Fig. 1 is a diagrammatic view in elevation of an encased core type transformer made in accordance with the teaching of this invention. The transformer casing and part of one winding of the transformer are shown in section;

Fig. 2 is an elevation view of a shell type transformer disposed in a liquid filled casing and embodying a modification of the cooling system arranged in accordance with the teaching of this invention. The transformer and casing are diagrammatically illustrated and shown in section;

Fig. 3 is a diagrammatic illustration in elevation of another modification of a cooling system arranged in accordance with this invention, adapted to an encased transformer of the shell type which is shown in section;

Fig. 4 is a diagrammatic illustration in elevation of still another modification of a cooling system arranged in accordance with this invention, also adapted to an encased transformer of the shell type which is shown in section;

Fig. 5 is another diagrammatic illustration in elevation of an encased transformer of the shell type which is shown in section with a cooling system adapted thereto in accordance with the teaching of this invention. While this cooling system is similar to that shown in Fig. 1 the baffle arrangement in the casing is modified to provide better cooling of the shell type transformer disposed as shown in this figure;

Fig. 6 is a diagrammatic illustration in elevation of a modified showing of an encased transformer of the shell type shown in section, with the heat dissipating radiating surfaces comprising the external walls of the casing; and

Fig. 7 is a cross sectional view taken along the line VII—VII of Fig. 1.

An electrical apparatus is disposed in a casing provided with heat dissipating means through which the cooling fluid is directed. Suitable dissipating means may be associated with the casing to be substantially a part thereof with adequate baffling to effect fluid paths passing along a wall surface which radiates heat to the surrounding air. These auxiliary paths may be made in any suitable manner as by baffling means within the casing but prefer-

ably are illustrated as radiators the ends of which are attached to the main portion of the casing at different levels; whether these auxiliary paths be along an external wall surface, or through a radiator they may be said to be auxiliary portions of the casing. In Fig. 1, a core type transformer 11 is disposed in a casing 12, with suitable heat dissipating radiators 13 and 14 disposed on opposite ends of the casing, being connected in fluid exchange relation with the casing by upper fluid conduits 21 and 22, respectively, and by lower fluid conduits 23 and 24, respectively. A cooling and insulating fluid 16 fills the casing. If the fluid is a liquid such as oil, its level is above the top of the upper fluid conduits, but a cooling and insulating gas would fill the entire casing. Additional radiators may be disposed along the sides of the casing, having conduit connections to the casing at 19 and 20.

As illustrated in Figs. 1 and 7, windings of the transformer comprise axially spaced superposed disk coils 27, which are separated by radially extending arcuately spaced disk spacers 26. Adjacent spacers 26 combine with the disk coils 27 to form horizontally disposed ducts 35 between the disk coils 27 and disk spacers 26. In the bore formed by the superposed disk coils 27 are concentric cylindrical barriers 29 and 29' which are separated to form vertically disposed ducts 28 and 28'. The spacing of these cylindrical barriers may be maintained by vertical spacing rods 30 between the barriers 29 and 29' and additional vertical spacing rods 30 between outer barrier 29' and the superposed disk coils 27. Inner vertical duct 28 is formed between barriers 29 and 29' and outer vertical duct 28' is formed between disk coils 27 and the outer barrier 29'. In abutment with the top disk spacers 26 and the top of the cylindrical barriers 29 and 29' are radially extending arcuately spaced end spacers 25. Adjacent end spacers 25 combine with the top disk coil 27 to form horizontally disposed inlet ducts 15. These inlet ducts 15 form passages for the flow of cooling fluid from the natural passageways in the casing 12 to the vertical ducts 28 and 28'. In similar manner radially extending arcuately spaced end spacers 25' are positioned in abutment with the bottom disk coil 27 and bottom of the cylindrical barriers 29 and 29' to form horizontally disposed outlet ducts 15'.

A part of the fluid entering inlet ducts 15 flows into and downwardly through the outer vertical duct 28'. The remainder of the fluid flowing through inlet ducts 15 flows into and downwardly through the inner vertical duct 28 and emerges from the outlet ducts 15'.

Fluid also enters the horizontal ducts 35 in the upper half of the winding and flows into the outer vertical duct 28'. Part of the fluid in the outer vertical duct 28' will emerge from the horizontal ducts 35 in the lower half of the winding. The remainder of the fluid in the outer duct will emerge from the outlet ducts 15'.

Baffle means is provided in the casing to aid in directing the flow of fluid to the ducts in the windings. In this instance, a horizontally disposed baffle 31 extends from the approximate outer peripheral surface of the winding 17 to the adjacent sides of the casing intermediate the upper and lower fluid conduits 21 and 23, providing a relatively small passageway 33 between the baffle and outer surface of the winding. A similar horizontally disposed baffle 32, which may be integral with baffle 31, is similarly arranged with respect to winding 18 and the sides of the casing adjacent thereto, extending from the approximate outer peripheral surface of the winding to the adjacent sides of the casing intermediate the upper and lower fluid conduits 22 and 24.

In Fig. 1 suitable means is provided for circulating the cooling fluid under sufficient head to move that fluid at a considerably increased rate through the radiators 13 and 14 when it is necessary to dissipate heat developed at an increased rate by the transformer. This includes intake 36, pump 38, and discharge 37. One end of the

intake is connected in fluid exchange relation with the lower portion of the casing near the connection of lower conduit 23, and the other end of the intake is connected in fluid exchange relation with the pump. The discharge 5 has its opposite ends connected in fluid exchange relation with the pump and the opposite lower portion of the casing near the connection of lower conduit 24. Baffle 34 is attached to the bottom of the casing and extends 10 upwardly to the proximity of baffle 31, thereby separating the lower portion of the casing into two compartments, one of which constitutes an intake compartment for the forced fluid system and the other of which constitutes a discharge compartment of that system. This baffle, however, is disposed in the casing so that it does 15 not interfere with the natural convection flow of the cooling fluid since it is upstanding intermediate the two windings.

Self-cooling by natural convection results in substantially identical fluid current paths on each side of this 20 baffle, and the direction of fluid flow through the winding is generally vertical. When the transformer becomes heated, the fluid flows by natural convection upwardly through the transformer coils 17 and 18 and from the upper portion of the casing it enters the upper ends of 25 radiators 13 and 14 through fluid conducting conduits 21 and 22, respectively. That fluid passes downwardly through the radiators as it cools, and then, of course, reenters the casing at the bottom thereof by passing through the lower fluid conducting conduits 23 and 24, respectively.

For forced cooling, that is, with the pump in operation, fluid is pumped into the casing from discharge 37. Some of this fluid passes upwardly through the winding 30 while other of this fluid passes in a generally parallel path upwardly through radiator 14. Then this fluid passes from the upper portion of coil 18 and from the top of radiator 14 to the left hand side of the casing as 35 viewed in Fig. 1 from which it is drawn by the pump to the intake in generally parallel paths that have a direction downwardly through the ducts in winding 17 and downwardly through radiator 13. Under conditions when forced fluid circulation is required for adequate cooling, it matters little whether the fluid circulates through the radiator 14 upwardly from the bottom of the casing or 40 downwardly from the top of the casing as the temperature differential of the fluid at the top and bottom of the casing is only a small percentage of the differential of temperature of fluid pumped through the radiator and ambient, and it is this latter differential which is relied upon to 45 cool the fluid.

The arrows shown in the figures represent fluid circulated by the forced fluid system; the arrow head indicates the direction of flow.

In Fig. 2 a sectional view of a three leg shell type 55 transformer is taken in a plane in front of an insulating washer 51 on which there are glued radially disposed spacers 52. Washers of this type are conventional in transformers and provide ducts for insulating and cooling fluid to pass between conventional adjacent disk coils (not shown). The cooling ducts are across the face of 60 the washer between spacers 52.

Radiators 53 and 54 are connected to opposite sides of the casing 55 to be in fluid exchange relation therewith. A baffle 59 is attached to the sides of the casing intermediate the upper and lower connections to the radiators. 65 This baffle, like the horizontal baffles of Fig. 1, extends from the sides of the casing approximately to the winding of the transformer so as to influence the fluid to flow through the winding.

Intake 56 of the forced fluid system apparatus has one 70 end thereof connected in fluid exchange relation with the upper portion of the casing and the other end thereof connected to pump 57, and discharge 58 has its lower end connected in fluid exchange relation with the bottom portion of the casing 55 and its upper end connected to 75 pump 57. The intake and discharge are connected on

opposite sides of the horizontal baffle. Lower leg 61 of the core may also constitute part of a baffle upstanding from the bottom of the casing which causes the fluid to flow transverse the winding when pump 57 is in operation, thereby improving the fluid flow into the winding and increasing the dissipation of heat of the transformer.

The flow of liquid by natural convection for the arrangement of Fig. 2 is conventional, taking similar paths on each side of the transformer, upwardly through the winding and into the radiators wherein it passes downwardly as it cools before reentering the casing at the bottom thereof.

When pump 57 is in operation, intake 56 draws fluid upwardly through both radiators, 53 and 54, and upwardly through the casing and transformer winding. This fluid passes through the pump to be discharged into the bottom portion of the casing, whence it passes in parallel paths upwardly through radiators 53 and 54 and upwardly through the transformer. In addition to this upward flow, the fluid flows transversely across the face of the washer because fluid discharged by the pump is directed by the baffles and influenced by impedance of the path through the winding to take the three parallel paths which means that some fluid must traverse the transformer winding to get to radiator 53.

The view of transformer 66 shown in Fig. 3 is similar to that of Fig. 2, a shell type transformer disposed in similar relation to its casing 67. Baffle 68 extends laterally between the transformer winding and the side walls of the casing approximately midway between the top and bottom of the casing. Lower leg, 71, of the core may constitute part of a baffle at the bottom of the casing extending upwardly to the approximate vicinity of the outer periphery of winding 69. In this modification only one heat dissipating unit is shown. This is radiator 72, external of the casing, disposed vertically with its upper end connected to header 76 that is in fluid exchange relation with the upper portion of the casing above baffle 68 and with its lower end connected to header 77 that is in fluid exchange relation with the bottom portion of the casing below baffle 68. In this embodiment the forced fluid system apparatus is also connected to these headers. Intake conduit 78 has its lower end connected to header 77 and its upper end connected to pump 81, and discharge conduit 79 has its upper end connected to header 76 and its lower end connected to the pump.

As in the previously described figures, the conventional flow of cooling fluid 82 by natural convection in the transformer shown in Fig. 3 is not interfered with by the provisions of the forced fluid system apparatus. For forced fluid circulation the pump, of course, is in operation and draws fluid from the casing on one side of baffle 68 and from one end of the radiator and discharges fluid into the casing on the other side of that baffle and into the other end of the radiator, thereby increasing the flow of fluid through the radiator and increasing the cooling effect of that fluid in contact with the transformer. In this illustration the intake conduit 78 draws fluid into header 77 from the bottom of the radiator 72 and from the bottom portion of the casing causing fluid to flow downwardly through winding 69 past baffle 68 and transversely of the winding above baffle 71. The fluid discharged by the pump passes from the discharge conduit 79 into header 76 and from there in parallel paths into radiator 72 and into the casing above baffle 68.

Another shell type transformer, identified by number 86, is illustrated in Fig. 4. In the casing of this modification an upstanding baffle 87 and a horizontal baffle 88 disposed around the coil 90 are like the similar baffles described in connection with Fig. 3. Radiators 95 and 96 are disposed on opposite sides of the casing, being connected thereto in fluid exchange relation. In this modification the forced fluid system apparatus includes, in

addition to pump 91, intake conduit 92 and discharge conduit 93, a vertical baffle 94 intermediate the top of the winding and at least the top of the fluid level in the casing to cause some fluid entering the casing from the pump discharge to flow crosswise of the transformer winding. Further, the intake and discharge of the pump are on opposite sides of the vertical baffles 87 and 94 and on opposite sides of the horizontal baffle 88. Intake 92 is connected to the lower portion of the casing to the left of baffles 87 and 94, and the discharge is connected to the upper portion of the casing to the right of baffles 87 and 94. Radiators 95 and 96 have their respective opposite ends connected directly to the casing, and preferably the upper ends of these radiators connect with the casing at a fluid level below the point where discharge conduit 93 connects to the casing and the lower ends of these radiators connect with the casing at a fluid level above the point where the intake conduit 92 connects to the casing.

Preferably, the direction of flow of fluid through the radiators when the pump is in operation is conventionally downward. Fluid discharged into the upper portion of the casing by the pump takes several generally parallel paths, a feature common to the various embodiments of this invention. In one path some fluid flows downwardly into and through radiator 96; in another path some of the fluid flows in a generally diagonal direction downwardly through coil 90 toward the intake conduit 92 disposed in the left hand bottom portion of the casing, and in a third path fluid traverses the upper portion of coil 90 below baffle 94 and enters the upper end of radiator 95 through which this fluid passes downwardly and is cooled. The fluid cooled in passing through radiator 96 flows transversely through the lower half of coil 90 because that fluid is discharged from the radiator into the bottom right hand portion of the casing from which it is drawn across the winding above baffle 87 to the intake conduit 92.

In Fig. 5 the arrangement of the casing, the horizontal baffle, the lower vertical baffle, the radiators and the pump and its associated intake and discharge conduits is similar to the arrangement of those parts described with respect to Fig. 1. However, the transformer shown in Fig. 5, is of the so-called shell type instead of core type of Fig. 1, and a baffle 97 is depended from the top of the casing to the approximate vicinity of the transformer core. Thus, this modification has the transformer and baffle arrangement shown in Fig. 4, but the pump apparatus arrangement of Fig. 1. The intake conduit of the pump apparatus 99 is connected in fluid exchange relation with the casing on the side of the lower upstanding baffle opposite to the side of the connection of the discharge conduit, but both the intake and discharge of this apparatus are connected to the casing below the level of the bottom of the radiators. With the structure thus arranged, the pump circulates fluid transversely across the bottom portion of the winding above the bottom upstanding baffle from the discharge conduit to the intake conduit as illustrated by arrow 41. Other of the fluid is circulated upwardly in the casing directed by horizontal baffle 98 to pass through the winding (arrow 42). Still other of the fluid (arrow 43) is circulated up through the radiator which has its intake nearest the discharge conduit of the pump, and from the upper end of that radiator the fluid pumped through that radiator enters the upper portion of the casing and is deflected by baffle 97 at the top of the casing so as to pass transversely of the upper half of the winding (arrow 44). The pump apparatus draws fluid from the bottom left portion of the transformer which results in fluid being drawn in parallel paths, some fluid (arrow 46) going into the top of the radiator to the left of the casing and other fluid (arrow 47) passing diagonally downwardly through the winding in the casing. Thus, in this arrangement the fluid circulated by the pump takes parallel paths through the winding and one or the other radiator.

Fig. 6 illustrates how the heat dissipating radiators may be incorporated into the casing by suitable baffling. Baffle or conduit means 101 are provided to separate the casing into a main portion 102 holding the transformer 103 and auxiliary portions 104 and 106 through which a cooling fluid such as an inert gas passes along heat dissipating surfaces 107 and 108, respectively. During self-cooling, the gas passes upwardly through the transformer in the main portion and downwardly through the auxiliary portions; whereas during forced flow, pump 109 discharges gas into the bottom right hand side of the casing and the horizontal and vertical parts of the baffle means cause that upwardly flowing gas to be directed in parallel paths through the transformer and through auxiliary portion 106. Gas is drawn into the intake conduit 112 of the pump apparatus from auxiliary portion 104 and from the left side of the main portion.

In all the modifications embodying this invention, the construction of the transformer, the radiators and the pump may be such that the impedances to the flow of fluid through the transformer and through the radiators and the head on the pump assure a considerable flow of fluid through all those paths effecting relatively fast dissipation of the transformer heat. That is, the impedance to fluid flow preferably is generally balanced through the casing and through the radiators.

Although but a few embodiments of the present invention have been illustrated and described, it will be apparent to one skilled in the art that various changes and modifications may be made therein without departing from the spirit of the invention or from the scope of the appended claims.

It is claimed and desired to secure by Letters Patent:

1. In combination, a device including a casing containing an apparatus subject to increases in temperature, a radiator external of said casing, means connecting said radiator in fluid exchange relation with said casing, said device being substantially filled with cooling fluid, said radiator disposed with said means comprising an upper conduit interconnecting the upper end of said radiator to an adjacent upper portion of said casing and a lower conduit interconnecting the lower end of said radiator to an adjacent lower portion of said casing whereby said fluid when heated flows by natural convection in series upwardly in said casing and downwardly in said radiator, and forced fluid flow means disposed independently of said natural convection series fluid path comprising a conduit connected at its opposite ends to said device and a fluid pump disposed intermediate said opposite ends to circulate said fluid from said pump through said casing and said radiator in the same vertical direction in parallel paths.

2. In combination, a casing, an apparatus subject to increases in temperature disposed in said casing, said apparatus spaced from the top and opposite sides of said casing, a pair of radiators external of said casing, a first of said radiators connected in fluid exchange relation with said casing at a first of said sides, a second of said radiators connected in fluid exchange relation with said casing at the other of said sides, said casing containing cooling fluid to a level above the connections to said radiators, baffle means disposed in said casing intermediate said opposite sides extending between said apparatus and said casing, whereby said fluid when heated has natural convection paths upwardly in said casing and downwardly in said radiators, and forced fluid flow means external of said casing disposed independently of said radiators including an intake conduit, a pump and a discharge conduit, said intake connected in fluid exchange relation with said casing on one side of said baffle means, said discharge connected in fluid exchange relation with said casing on the opposite side of said baffle means, whereby said pump causes fluid to flow transversely in said casing.

3. In combination, a casing, an apparatus subject to

increases in temperature disposed in said casing, said apparatus spaced from the top and opposite sides of said casing, a pair of radiators external of said casing, a first of said radiators connected in fluid exchange relation with said casing at a first of said sides, a second of said radiators connected in fluid exchange relation with said casing at the other of said sides, said casing containing cooling fluid to a level above the connections to said radiators, baffle means disposed in said casing intermediate said opposite sides extending between said apparatus and the bottom wall of said casing, whereby said fluid when heated has similar natural convection paths on each side of said baffle means upwardly in said casing and downwardly in said radiators, and forced fluid flow means external of said casing disposed independently of said radiators including an intake conduit, a pump and a discharge conduit, said intake connected in fluid exchange relation with said casing on one side of said baffle means, said discharge connected in fluid exchange relation with said casing on the opposite side of said baffle means, whereby said pump causes transverse fluid flow in said casing, said intake disposed to draw fluid from the bottom of a first of said radiators and the adjacent bottom portion of said casing, said discharge disposed to expel fluid into the bottom of the second of said radiators and the adjacent bottom portion of said casing under sufficient head to cause some of said fluid to flow upwardly through said second radiator and upwardly through said casing and whereby the fluid drawn from said first radiator by said intake enters said first radiator from the upper portion of said casing.

4. In combination, a casing, an apparatus subject to increases in temperature disposed in said casing spaced from one side of said casing, said apparatus provided with fluid passages therethrough, a radiator external of said casing connected at its top and bottom in fluid exchange relation with said casing, said casing containing cooling fluid at a level above the connections to said radiator, baffle means disposed in said casing intermediate the top and bottom of said radiator between said apparatus and said side to cause said fluid when heated to flow by natural convection upwardly in said casing through said fluid passages in series hydraulic circuit with the downward flow through said radiator, and forced fluid flow means independent of said natural convection path through said radiator, said forced flow means including an intake conduit, a discharge conduit and a fluid pump connected between said conduits, said intake connected in fluid exchange relation with said casing on one side of said baffle means at a level as low as the bottom of said radiator, said discharge connected in fluid exchange relation with said casing on the opposite side of said baffle means at a level as high as the top of said radiator to cause fluid circulated by said pump to pass through both said apparatus and said radiator in hydraulic parallel paths.

5. In combination, a casing, an apparatus subject to increases in temperature disposed in said casing spaced from one side of said casing, said apparatus provided with fluid passages therethrough, a radiator external of said casing connected at its top and bottom in fluid exchange relation with said casing, said casing containing cooling fluid at a level above the connections to said radiator to cause said fluid when heated to flow by natural convection upwardly in said casing through said fluid passages in series hydraulic circuit with the downward flow through said radiator, and forced fluid flow means independent of said natural convection path through said radiator, said forced flow means including an intake, a discharge and a fluid pump connected between said intake and said discharge, said intake connected in fluid exchange relation with said casing at a level as low as the bottom of said radiator, said discharge connected in fluid exchange relation with said casing at a level as high as the top of said radiator to cause

fluid circulated by said pump to pass through both said apparatus and said radiator in hydraulic parallel paths.

6. In combination, a casing, an apparatus subject to increases in temperature disposed in said casing and spaced from the top and opposite sides of said casing, a pair of radiators external of said casing, a first of said radiators connected in fluid exchange relation with said casing to a first of said sides, a second of said radiators connected in fluid exchange relation with said casing to the other of said sides, said casing containing cooling fluid to a level above the connections to said radiators, whereby said fluid when heated has natural convection paths upwardly in said casing through said apparatus and downwardly in said radiators, and forced fluid means external of said casing disposed independently of said radiators including an intake, a pump and a discharge, said intake connected in fluid exchange relation with said casing near the bottom portion of said first side to draw fluid from the bottom of said first radiator and from the adjacent bottom portion of said casing, said discharge connected in fluid exchange relation with said casing near the bottom portion of said other side to expel fluid into the bottom of said second radiator and the adjacent bottom portion of said casing.

7. In combination, a casing, an apparatus subject to changes in temperature disposed in said casing, said apparatus having fluid passages therethrough, a pair of radiators external of opposite sides of said casing, a first of said radiators connected in fluid exchange relation with said casing to a first of said sides, a second of said radiators connected in fluid exchange relation with said casing to the other of said sides, said casing containing cooling fluid to a level above the connections to said radiators, baffle means disposed in said casing intermediate the top and bottom of said casing extending between said apparatus and said opposite sides, and forced fluid flow means external of said casing disposed independently of said radiators including an intake, a pump and a discharge, said intake connected in fluid exchange relation with said casing to one side of said baffle means, said discharge connected in fluid exchange relation with said casing to the opposite side of said baffle means, the head on said pump being sufficient when said pump is in operation that fluid discharge from said pump will flow in parallel paths through the passages in said apparatus and through said radiators.

8. In combination, a casing, an apparatus subject to changes in temperature disposed in said casing spaced from the top and opposite sides of said casing, a radiator external of said casing connected thereto at its opposite ends in fluid exchange relation at the top and bottom portions of a side of said casing, said casing containing cooling fluid to a level above the connections of said radiator to said casing, baffle means disposed in said casing intermediate the top and bottom of said casing extending between said apparatus and said sides, and forced fluid flow means external of said casing disposed independently of said radiator including an intake, a pump and a discharge, said intake connected in fluid exchange relation with said casing at a level as high as the top of said radiator, said discharge connected in fluid exchange relation with said casing at a level as low as the bottom of said radiator, whereby fluid circulated by said pump passes through both said apparatus and said radiator.

9. In combination, a casing, an apparatus subject to increases in temperature disposed in said casing, said apparatus spaced from the top and opposite sides of said casing, a pair of radiators external of said casing, a first of said radiators connected in fluid exchange relation with said casing at a first of said sides, a second of said radiators connected in fluid exchange relation with said casing at the other of said sides, said casing containing a cooling fluid to a level above the connections to said radiators, baffle means disposed in said casing intermediate said opposite sides extending between said apparatus and the

top of said casing, whereby said fluid when heated has similar natural convection paths on each side of said baffle means upwardly in said casing and downwardly in said radiators, and forced fluid flow means external of said radiators, and forced fluid flow means external of said casing disposed independently of said radiators including an intake, a pump and a discharge, said intake connected in fluid exchange relation with said casing on one side of said baffle means, said discharge connected in fluid exchange relation with said casing on the opposite side of said baffle means, whereby said pump causes fluid to flow transversely in said casing, said intake disposed to draw fluid from the bottom of said first radiator and the adjacent bottom portion of said casing, said discharge disposed to expel fluid into the top of said second radiator and the adjacent top portion of said casing.

10. In combination, a casing, an apparatus subject to increases in temperature disposed in said casing, said apparatus spaced from the top and opposite sides of said casing, a pair of radiators external of said casing, a first of said radiators connected in fluid exchange relation with said casing at a first of said sides, a second of said radiators connected in fluid exchange relation with said casing at the other of said sides, said casing containing cooling fluid to a level above the connections to said radiators, baffle means disposed in said casing intermediate said opposite sides extending between said apparatus and the top of said casing, whereby said fluid when heated has similar natural convection paths on each side of said baffle means upwardly in said casing and downwardly in said radiators, and forced fluid flow means external of said casing disposed independently of said radiators including an intake, a pump and a discharge, said intake connected in fluid exchange relation with said casing on one side of said baffle means, said discharge connected in fluid exchange relation with said casing on the opposite side of said baffle means, whereby said pump causes fluid to flow transversely in said casing.

11. In combination, a casing containing cooling fluid, an apparatus subject to changes of temperature disposed in said casing, a heat exchanger disposed outside said casing and connected in fluid exchange relation at its opposite ends to the top and bottom of said casing, said apparatus being provided with fluid passages therethrough to cause said fluid when heated to flow by natural convection upwardly in said casing through said fluid passages in series hydraulic circuit with the downward flow through said heat exchanger and a forced fluid means connected in fluid exchange relation with said casing, said forced fluid means including a fluid pump external of said casing and independent of said heat exchanger so as not to interfere with natural convection flow of said fluid when not in operation and being disposed in fluid exchange relation with said casing and said heat exchanger so as to cause fluid to flow in the same vertical direction in hydraulic parallel paths through said passages and said heat exchanger when said pump is in operation due to the relative impedance to fluid flow in said two hydraulic parallel paths.

12. In combination, a device including a casing containing an apparatus having fluid passages therethrough and subject to changes of temperature, said device substantially filled with cooling fluid and having a radiator external of said casing and means connecting opposite ends of said radiator in fluid exchange relation with the top portion and bottom portions of said casing to cause said fluid when heated to flow by natural convection in series hydraulic circuit upwardly in said casing and downwardly in said radiator, the impedance to fluid flow in said casing being approximately equal to the impedance to fluid flow in said radiator, and forced fluid flow means comprising a conduit connected at its opposite ends to said device and including a fluid pump disposed intermediate said last mentioned opposite ends, said pump when in operation having sufficient head to force said

11

fluid to flow through said casing and said radiator in the same vertical direction in hydraulic parallel paths.

13. In combination, a casing containing a cooling fluid, an apparatus subject to increases in temperature disposed in said casing, a heat exchanger connected in fluid exchange relationship at its opposite ends to points of said casing at different levels, said apparatus being provided with fluid passages therethrough allowing said fluid when heated to flow by natural convection in a complete circuit generally upwards through said casing and generally downwards through said exchanger and forced fluid flow means, said forced fluid flow means disposed out of said circuit in fluid exchange relationship with said casing to cause the forced flow of fluid through said casing to be in the same vertical direction as the forced flow of fluid

through said exchanger, said forced fluid flow means being external of said casing and independent of said exchanger so as not to interfere with natural convection of said fluid when said flow means is not in operation.
